(57) **CLAIM**

The ornamental design for an automobile driving simulator, as shown and described.

DESCRIPTION

FIG. 1 is a left front perspective view of the automobile driving simulator showing our new design;

FIG. 2 is a right front perspective view thereof;

FIG. 3 is a front elevational view thereof;

FIG. 4 is a rear elevational view thereof;

FIG. 5 is a top plan view thereof;

FIG. 6 is a left side elevational view thereof; and,

FIG. 7 is a right side elevational view thereof.

The broken lines illustrate environmental structure and form no part of the claimed design.
